UNITED STATES PATENT OFFICE.

EMIL TYDEN AND SAMUEL B. DOVER, OF CHICAGO, ILLINOIS, ASSIGNEES TO
THE WESTERN PLANTER MANUFACTURING COMPANY, OF SAME PLACE.

PLANTER.

SPECIFICATION forming part of Letters Patent No. 453,330, dated June 2, 1891.

Application filed March 29, 1889. Serial No. 305,281. (No model.)

To all whom it may concern:

Be it known that we, EMIL TYDEN and SAMUEL B. DOVER, both citizens of the United States, residing at Chicago, in the county of 5 Cook and State of Illinois, have invented certain new and useful Improvements in Planters, of which the following is a full and exact specification.

Our invention relates to seed-planters, and 10 particularly to that class of implements adapted to plant two parallel rows of corn simultaneously; and it consists of certain improvements in the frame of the machine and in the drop mechanism, as will be hereinafter 15 more particularly specified.

In the drawings, Figure 1 is a perspective view of the planter with one hopper opened to expose the drop mechanism. Fig. 2 is a side perspective view with both hoppers 20 closed. Fig. 3 is a detail perspective view of the drop mechanism. Fig. 4 is a detail plan view of a pawl and the means for retaining it on its trunnion. Fig. 5 is a side view of the same part. Fig. 6 is a plan view of the bottom 25 plate of the hopper in which the drop-disk is seated. Fig. 7 is a sectional view of the cut-off for removing the surplus grain from the drop-plate cups. Fig. 8 is a perspective view of a guideway which leads the grain to 30 the cut-off in a narrowed stream. Fig. 9 is a plan view of the beam-plate on which the hopper rests. Fig. 10 is a sectional view showing the hopper drop mechanism and the leg through which the corn is dropped to earth.

35 Fig. 11 is a sectional view of parts of the drop mechanism and of the valve which determines the time of dropping the grain. Figs. 12 and 13 are detail views illustrating the means for securing the cover of the hopper in 40 place. Fig. 14 is a side elevation of the planter, the runners being lowered into ground. Fig. 15 is a detail section of an axle-trunnion. Fig. 16 is a plan view of the skeleton frame of the planter. Fig. 17 is a perspective view 45 showing the general construction of the wheel-frame of the planter. Fig. 18 is a perspective view of the lever and its foot balancing-arms. Fig. 19 is a longitudinal section of the arc and the tube upon which it is mounted, taken on 50 line 2 2 of Fig. 17. Fig. 20 is a view of the

trunnion at the bottom of the arc, showing the means of attaching the brace of the wheel-frame thereto. Fig. 21 is an elevation of one of the side bars of the planter. Fig. 21¹ is a detail section of the line 5 5 on Fig. 16. Fig. 55 22 is an elevation of the front bar of the runner-frame. Fig. 23 is an elevation of a strut belonging to the same. Fig. 24 is a transverse section of the strut, taken in line 3 3 of Fig. 23. Fig. 25 is a detail perspective view indicating the means of attachment of the runner to the end of the front bar. Fig. 26 is an elevation of the bar which supports the driver's seat. Fig. 27 is a perspective view of the scraper which clears the carrying-wheels from 65 accumulations. Fig. 28 is a perspective view of a casting for attaching the same to the scraper-bar. Fig. 29 is a detail perspective of the hooked or threaded end of the brace-rod of the wheel-frame. Fig. 30 is a view of 70 the arm which operates the scraper-bar, together with its attendant parts. Fig. 31 is a sectional view taken on line 4 4 of Fig. 30.

Like letters indicate similar parts throughout the several views.

The frame of the planter will be first described, and reference is now had particularly to Figs. 15 and 17. It is made up of a wheel-frame and a runner and planter frame flexibly united, as will appear from the detail description. It is especially desirable that such frames shall be strong, yet light and elastic, and that all parts shall be of simple construction.

The axle A¹⁰, which carries the wheel-frame, 85 is of tubing A, provided at either end with a trunnion A', clamped in position by the bolts a a'. This clamping is made possible by bifurcating the walls of the trunnion with the longitudinal openings a², separating the chambered portion into halves, which may be readily sprung into contact with the tube. The chamber of each trunnion tapers at its inner end to form an inclined seat a', which allows for any irregularity of the casting and 95 further insures the solidity of the contact.

Each of the side bars B¹⁰ of the frame, as shown also in Fig. 21, is composed of two pieces of bar iron or steel arranged as a truss, in which the trunnion serves as a strut. Their 100

rear ends form a cylindrical bearing b , which carries the scraper-bar. The forward end of the upper bar B is produced beyond the end of the lower bar B' to form a hinge-socket b^2 for a pin, and is then returned rearwardly below the lower member of the side bar, to which it is secured by the end a^5 of the brace A^2 . The trunnion A' is extended above and below to form seats for the two elements of the side bar, the bolt a fastening them thereon. Side flanges a^3 prevent side motion and locate the position of the parts. A lever-arc C is carried upon the tube A midway in its length and is secured in position by a bolt c , passing through its hub and through the tube. The arc is provided with a trunnion c' , as shown most clearly in Fig. 19, to receive the eye a^4 of the brace A^2 , also held by the bolt c . A seat-support A^3 extends upwardly and rearwardly from the arc, forming a member of a tripod, which is completed by the double brace A^4 , mounted upon the rear ends of the side bars B^{10} and held between its members B and B' . The bolts $b^3 b^3$, which bind these parts together, also secure the ends of the brace. The extended end of the seat-support, which preferably returns upon itself, Fig. 26, is a portion a^4 , and increases its strength and carrying capacity. The brace A^2 , of V form, is turned upwardly at right angles at each end to form a threaded portion a^5 , which passes through and secures the members of the side bars together and closes the hinge-sockets b^2 . At its center a loop or eye a^4 serves to attach it to the arc, as before described, and to thus rigidly tie the brace and parts of the entire wheel-frame together. The scraper-bar D is also of tubing loosely confined in the end bearings b of the side bars and carries upon each end a scraper E , which serves to clear the planter-wheels from accumulations. These scrapers are in two parts, Figs 27 and 28—a body-piece e , of any satisfactory contour to suit the surface of the wheel, and a clamping portion e' to secure it to the bar. The one casting has projecting lugs e^2 , adapted to receive complementary lugs e^3 , extending from the other casting, and to form therewith a hinging connection. A bolt passes through the apertures e^4 and e^5 and firmly clamps the scraper in position upon the bar. By this arrangement of parts the scrapers may be accurately adjusted to the surface of the wheels and an even contact maintained therewith not obtainable were they pinned fixedly to the bar. One end of the brace A^4 may be extended beyond one of the side bars and be notched at a^6 , Fig. 30, to receive the flange f^4 of an arm F , pinned upon the scraper-bar D as a means of its rotation. The bar is thus locked against end motion and maintains the lateral position of the scrapers. A stop f prevents undue rotation of the bar and holds the scrapers a proper distance from the surface of the wheel when they are not in use, and yet in such proximity that they may be readily applied whenever it is desired to do so.

The lever G^{10} is preferably constructed of two parts, the one G having the operating-arm g extending upwardly and provided with the usual latching devices and the other G' riveted or otherwise secured to it to form a bifurcated lever, between the parts of which the arc C is received. Both parts have rearwardly-projecting foot-arms g^2 and foot-rests g^3 and also forwardly-extending arms g^4 , which may be provided with a foot-rest similar to that of the rear arms, or, if preferred, may have the rest g^5 formed of tubing secured between the ends of the two castings. As will be seen by referring to Figs. 1, 2, and 18, this compound lever is fulcrumed or pivoted directly on the cylindrical axle A and has bearings thereon widely separated, thus obtaining the greatest stability and strength laterally and pivotally, together with the utmost simplicity of parts. The arc locates its position and prevents side motion.

In planters it is requisite that great leverage be given the foot-arms to secure ease in the raising and lowering of the runner-frame to regulate the depth of planting. These arms are in the form of a triangle, the base of which is the tube, thus obtaining steadiness of operation. The links connecting the lever to the tongue projecting through the runner-frame are pivoted to it in the apertures g^6 .

By the arrangement of parts described as constituting the wheel-frame great strength and flexibility are obtained. This flexibility is particularly desirable in the side bars, since they control the position of the runners, and if rigid would prevent them from following, as is necessary, the irregularities of the ground over which they pass. They may be given more or less spring, as is found desirable, by the method shown in Fig. 21^a, the aperture b^4 in the bar B' being here shown of such size as to permit play of one bar upon the other. The form of bars shown in Figs. 17 and 21 are found to be very satisfactory and possess sufficiently the qualities of elliptical springs to secure the desired results. It will be observed, also, that the seat, which is supported principally upon the extreme rear ends of the bars, is cushioned by this same spring action. The draft strain delivered to the bars at the hinge-sockets b^2 is evenly divided and carried to both sides of the strut and delivered on both ends of the bolts $a a$, rendering the strain very equable.

The runner-frame of the planter will now be described. The main beam I , to which the hoppers and the seed-legs are attached, is of angle-steel, and the front beam H is of bar-steel, arranged as a truss in form somewhat similar to the side bars previously described. Bolts $h h$ fasten these bars together at their ends, and struts $H' H'$ hold them apart at their middle. The struts have holes $h' h'$, through which to insert a pin to secure the tongue to the frame and to adjust its height to suit the size of the team employed for draft

- purposes. An aperture h^2 in each serves for the insertion of the hooked end of a brace I' , the rearward end of which is bent and threaded for attachment in the main beam, 5 the hinge-casting I^2 being secured to the beam by it. The frame is strongly braced by these ties and the draft strain transmitted by them directly from the tongue to the ends of the side bars, Fig. 16, and thence to the wheel- 10 trunnions and sideward to the seed-legs and runners. By this direct distribution of strain it is rendered practicable to construct the beams very light and of but little strength. The main beam serves, essentially, as a strut 15 and the front beam as a means for maintaining the front ends of the runners at their proper lateral distances and to exert downward pressure in forcing them into ground. The tongue of the planter is carried to the 20 rearward from the strut H' through strap i , Fig. 1, on the main beam and to a point below the front end of the lever-arms g^4 , to which it is attached by connection-bars g^7 , Fig. 14.
- The drop mechanism will now be described. 25 A foundation-plate J rests directly upon the beam I , to which it is secured by the clip projections j , Figs. 3, 9, and 10. A bolt J' fastens it firmly at the rear to the leg K , through which the seed is dropped to earth. The 30 front of the plate is provided with hinge-lugs j' , which register with corresponding lugs l on the bottom casting L of the hopper and serve as a pivotal point for the swinging of the entire hopper attached thereto into an 35 open position, as indicated in Figs. 1 and 3. When thus open the drop mechanism is exposed to view for repairing, cleaning, and for the exchange of the drop-plate for others of different-sized apertures. A spring j^2 locks 40 the hopper when closed. The bottom casting L has a central cylindrical opening l' , in which rotates the drop-plate M , pivoted on a trunnion l^2 , projecting from the covering-lug L^2 of the casting L . This plate M when the 45 hopper is closed receives the corn in its cups m and carries it under the cut-off N , where it is dropped into leg K and thence to ground. By making these cups open and tapering toward the periphery of the disk and providing 50 a recess l^3 in the cylindrical walls in which the disk revolves at the point where the contents of the cup are to be dropped the compression due to forcing the grain into the cups is relieved and the grain is dropped out 55 with great certainty. It is found that when the cups are cylindrical and closed on all sides clogging is of frequent occurrence and the consequent missing of hill after hill possible.
- 60 The cylindrical opening l' of the castings L is closed at the bottom by the pivoted plate L' , upon which the drop-plate M rests and revolves. This plate is provided with an aperture l^4 , through which the grain is dropped 65 when a seed-cup registers therewith. It will be readily understood that when the plate L' is closed the hopper may be opened and
- shut without the loss of any grain therefrom and that a very ready means for changing drop-plates without removing the grain from the hopper is obtained.
- The drop-plate M is provided with lugs m' , which, when the hopper is closed, are engaged by lugs o on the pawl-wheel O , operating through a central opening l^5 in the supplementary plate, and the plate thus given motion. The pawl-wheel rests upon and within the foundation-plate J and is pivoted on a trunnion j^3 , projecting therefrom. A slide P is arranged to seat and be reciprocated in recesses j^4 in the foundation-plate J and has pawls R , adapted to give motion to the pawl-wheel in the usual manner. These pawls are pivoted on trunnions P' , having on their outer end a lug p , projecting beyond their bearing-surface in such form that the pawl having a corresponding recess r is permitted to pass over it when the free end is held above its normal position, but to be retained by it when in operative position. The slide P is 90 provided with lugs p' so placed that the lugs o' upon the pawl-wheel engage with them at the end of each reciprocation and lock the wheel from further movement between it and the operating-pawl. This is for the purpose 95 of maintaining the registry of the seed-cups with the aperture l^4 in the plate L until the grain has time to drop.
- A convenient means for attaching the reciprocating connection-bar P^2 to the slide P 100 is shown in Fig. 3. The bar is received below a portion of the slide p^2 , which prevents it rising from its place when once seated upon the pin p^3 . The slide P is provided with a wing portion p^4 , Figs. 9, 10, and 11, which has 105 motion below the plate J at the opening j^5 and serves to oscillate the foot-valve S . The wing is so proportioned as to only permit the passage of the grain dropped when the foot-valve is nearly at the end of an oscillation. 110 Scattering of grain is thus prevented. The slide P is locked in its seat by the wing projecting below the beam-plate, but may be conveniently removed by bringing it to register with the aperture j^5 and lifting first the opposite side from the recess in which it slides. 115 The valve S is of spring-steel pivoted on a bolt T midway in the length of the leg. The travel given the top of the valve is somewhat in excess of what is required for its foot to 120 traverse the space between the walls of the chamber in which it moves, a slight pressure against the wall at each end of the stroke being the result. This pressure serves to insure a perfect closing of the valve and the retention of the grain by it. It also allows the slide to obtain full headway before it releases the grain, and then affords a quick release, 125 which prevents a scattering of the grain.
- Other points of advantage are that the slide 130 is brought to rest at each end of its stroke without jar and that it cannot be broken by obstructions forcing themselves into the leg. The aperture through which the pivoting-bolt

T passes is made by forcing the portions s s' downwardly and the portion s' upwardly to form a cylindrical bearing.

To prevent clogging of grain, the lifting of the chisel of the cut-off unnecessarily, and the possibility of grain catching under its corners, a narrowed way U is formed by abutment-walls u and u' to conduct the grain in a narrowed stream to it. A chisel N, pivoted on trunnions n , integral with it, clears off the surplus grain from the cups of the drop-plates. These trunnions are seated in bearings in the plate L on or about the plane of cut-off, a smoother operation being obtained by this arrangement than by that in which the pivotal point is above the plane of cut-off. The cap casting N', which covers the cut-off chisel and its spring, is provided with recesses n' , into which the trunnions of the cut-off are received and held, a single bolt n^2 serving to secure all the parts together.

Referring to Figs. 10, 12, and 13, W is the cover of the hopper, and W' a metallic bar or spring secured to it on its under side. This spring is adapted to engage with lugs w , projecting from the casting, when the cover is seated between the guide-lugs w' and moved forward. The lugs w^2 serve as stops, and the cover when in the position indicated in Fig. 13 is firmly secured.

Other methods besides that of hinging will be found to be satisfactory for holding the hopper in position and yet allow it to be opened for disclosing the drop mechanism. It is not desired to narrowly cover this. The important feature of this part of the invention is the location of the drop-plate within or below the bottom plate of the hopper and the use of a supplementary floor-plate which affords a bottom cover to its seed-cups, which can be readily removed or from which it can be taken, but when in operative position allows the drop-plate to be carried with the bottom plate of the hopper and acts as a floor-plate to protect it and the hopper against loss of grain which is contained in the latter at the time. It is further desired in the matter of the side bars of the planter to cover these not only as trusses, but as springs, which have merits over a rigid bar.

We claim—

1. In combination with a fixed axle of a planter, a trunnion comprising a tubular socket or sleeve adapted to receive the end of the axle, such sleeve having the longitudinal opening a^2 and being clamped onto the axle, substantially as set forth.

2. In a planter-frame, the side trusses, each having its upper and lower bars made of one piece folded upon itself to form an eye or bearing at the fold, and the shaft D, journaled in such eyes, substantially as set forth.

3. In a planter, in combination with the axle of the supporting-wheels and the wheel-frame of which it is a part, the planter-frame hinged to such wheel-frame, and a tilting lever

pivoted upon the axle and having its axis coincident with that of the wheels and having an arm connected to the planter-frame, whereby the relation of the two frames to each other may be adjusted by rocking the lever about the axis of the supporting-wheels, substantially as set forth.

4. In a planter, in combination with the axle of the supporting-wheels and the wheel-frame of which it is a part, the planter-frame hinged to such wheel-frame, and a tilting lever rocking over the axle, and an arc to which said tilting lever is adapted to be locked, such arc being secured directly upon the axle, substantially as set forth.

5. In a planter, in combination with the wheel-frame having the axle of the supporting-wheels rigid with it, the tilting lever journaled upon such axle and having its axis coincident with that of the wheels, and an arc rigid with the axle, to which said lever is adapted to be locked, and the seat having a support directly attached to such arc, substantially as set forth.

6. In a planter, in combination with the double brace A^4 , the seat-support A^3 , extended across the brace A^4 and provided with a portion a^7 , which turns upon itself below the brace A^4 , said seat-support being attached to said brace A^4 both at the point where it crosses the brace A^4 above the latter and at the point where the portion a^7 returns below said brace, substantially as set forth.

7. In a planter, in combination with the axle of the supporting-wheels and the side trusses rigidly attached to such axle at its ends, the braces $A^2 A^2$, rigidly attached to the axle at the middle and to the trusses, respectively, at their forward ends, substantially as set forth.

8. In a planter, in combination with the axle of the supporting-wheels, the brace $A^2 A^2$, attached rigidly to the axle at the middle and having the ends bent at right angles to the body and inserted in holes provided in the trusses, whereby it is attached to the trusses at the ends, substantially as set forth.

9. In a planter, in combination with the axle of the supporting-wheels and the side trusses rigidly attached to such axle, the double brace $A^2 A^2$ in one piece, having its two arms bent at an angle to each other and formed with an eye at such angle, whereby said brace is adapted to be secured to the axle by one bolt at such eye, substantially as set forth.

10. In a planter, in combination with the axle of the supporting-wheels, the side trusses rigidly attached to the axle at its ends, the arc having its hub encircling the axle at the middle and provided with a downwardly-projecting boss, the double brace $A^2 A^2$, having its arms bent at an angle to each other and formed with an eye at such angle adapted to receive said boss, said hub having a bolt-aperture piercing it at said boss, and a bolt inserted

through such aperture and provided with a suitable stop, whereby a single bolt serves to retain the eye on the boss and attach it to the hub and to the axle and to secure the hub to the axle, substantially as set forth.

5 11. In combination, substantially as set forth, the scraper-bar D, the arm F, fixed thereto, having the flange f^4 , the side bars in which said scraper-bar is journaled, and the brace A^4 , secured to said side bars adjacent to the bearing of the scraper-bar therein, said brace having the notch a^6 wherein the flange f^4 is lodged, substantially as set forth.

12. In combination with the scraper-bar D and the arm F, secured thereto, having the flange f^4 , the side bars having the bearings in which said scraper-bar D is journaled, and the brace A^4 , secured to said side bars adjacent to said bearing of the scraper-bar and having a notch a^6 , in which said flange f^4 is lodged, said arm F having the stop projection f projecting laterally from the upper end of the flange f^4 , whereby the throw of the scraper-bar rearwardly is limited, substantially as set forth.

25 13. In a planter, in combination with the wheel-frame and planter-frame hinged together, the lever for adjusting them to each other, rocking over the bearing on the wheel-frame, said lever being bifurcated at its lower part, the two ends produced by such bifurcation being made to diverge laterally and each being journaled on said bearing at a distance apart, whereby said lever is given stability, substantially as set forth.

30 14. In a planter, in combination with the wheel-frame and planter-frame hinged together, the lever by which they are adjusted to each other, bifurcated at its lower part and having its two ends thus formed journaled upon the bearing on the wheel-frame at considerable distance apart, and an arc to which said lever is adapted to be locked in its adjustment, rigidly fixed on said bearing between the bifurcated arms of the lever and adapted to contact them both laterally, whereby said arc further increases the stability of the lever, substantially as set forth.

45 15. In combination with the wheel-frame and planter-frame hinged together, the lever by which they are adjusted to each other, formed of two parts, one of said parts having the operative arm extending upwardly, each of said parts having both rearwardly and forwardly extended arms, said two parts being widely separated at their lower ends and at said ends journaled on the wheel-frame, their bearings having a common axis, the forwardly-extending arms of the two parts being joined at the forward end and the rearwardly-extending parts being joined at the rear end, whereby the said two bearings of said lever are braced in three directions, thereby giving said lever great rigidity and stability, substantially as set forth.

55 16. In a planter, a runner-frame or planter-

frame comprising an angle-iron bar I, extending transversely from side to side of the frame, having a horizontal and a vertical lip, and the legs K, secured to the vertical lip, and the base of the dropping mechanism secured to the horizontal lip, substantially as set forth.

70 17. In a planter, in combination with the strut H', having the aperture h^2 , the brace I', having the hooked end adapted to be inserted in said aperture, substantially as and for the purpose set forth.

75 18. In a planter, in combination with the runners, the truss which forms the front beam of the planter-frame, having one of its members bent vertically at the end, the runner having its point extended and secured to said bent end, substantially as set forth.

80 19. In a planter, in combination with the wheel-frame and the planter-frame hinged thereto, the hinged casting I² and the brace I', connected at its forward end to the front bar of the runner-frame and having its rear end provided with a bent portion inserted through the rear transverse bar of the rear frame and through the hinge-casting and adapted to be secured in place by a nut, substantially as set forth.

85 20. In a planter, in combination with the wheel-frame having side bars and the planter-frame hinged to said wheel-frame at the forward end of said side bars, said planter-frame having its forward bar consisting of a truss with a strut at its middle part, a tongue passing through said strut, and braces extending from said strut at opposite sides of the tongue, diverging rearward, and connected, respectively, to the rear bar of the planter-frame directly in front of the forward ends of the side bars of the wheel-frame, substantially as set forth.

90 21. In a planter, in combination with the hopper and the drop-plate carried by the hopper in its bottom, a fixed base to which said hopper is hinged, and feeding-pawl mechanism supported on said base and having parts which project upward and engage the drop-plate when the hopper is upright on the base, but which permit the hopper to be rocked over its hinge and carry the drop-plate up away from said feeding mechanism without deranging the latter, substantially as set forth.

95 22. In a planter, in combination with a foundation-plate J, having an aperture j^3 , the slide which operates as a valve to close said aperture and having a downwardly-extending projection j^3 , the seed-leg of the planter secured to the foundation-plate and communicating with the aperture j^3 , and an oscillating foot-valve in said seed-leg having its upper end engaged by the projection j^3 , substantially as set forth.

100 23. In a planter, in combination with the bottom plate of the hopper, the cut-off operating therein, the abutment-walls of the seed-channel in said bottom plate converging to narrow the portion at the vicinity of the cut-

off to diminish the duty required thereof, substantially as set forth.

24. In a planter, in combination with the bottom plate having the circular seed-channel, the drop-plate M, the chisel cut-off extending in a direction tangential to the channel and pivoted outside the circle bounding the latter, having its edge operating at the plane of the upper surface of the drop-plate and having its pivot substantially at the said

plane of operation of its edge, substantially as set forth.

In witness whereof we hereunto subscribe our names this 25th day of March, A. D. 1888.

EMIL TYDEN.
